US00D901448S

(12) **United States Design Patent** (10) **Patent No.:** **US D901,448 S**
(45) **Date of Patent:** **** Nov. 10, 2020**

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/658,595**

(22) Filed: **Aug. 1, 2018**

Related U.S. Application Data

(63) Continuation of application No. 29/617,528, filed on Sep. 14, 2017, now Pat. No. Des. 827,615, which is (Continued)

(57) **CLAIM**

The ornamental design for an electronic device, as shown and described.

DESCRIPTION

FIG. 1 is a front perspective view of an electronic device showing our new design;

FIG. 2 is a rear perspective view thereof;

FIG. 3 is another front perspective view thereof;

FIG. 4 is another rear perspective view thereof;

FIG. 5 is a front view thereof;

FIG. 6 is a rear view thereof;

FIG. 7 is a left side view thereof;

FIG. 8 is a right side view thereof;

(Continued)

FIG. 9 is a top view thereof; and, FIG. 10 is a bottom view thereof. The dashed broken lines illustrate structure or features that form no part of the claimed design. The oblique shade lines illustrate a glossy surface. The black shading illustrates a black surface. The gray shading illustrates a metallic surface.

1 Claim, 5 Drawing Sheets

Related U.S. Application Data

a continuation of application No. 29/578,397, filed on Sep. 21, 2016, now Pat. No. Des. 805,058, which is a continuation of application No. 29/526,019, filed on May 5, 2015, now Pat. No. Des. 771,597.
